Patented May 1, 1962

192,687

TELEVISION ANTENNA

Marvin P. Middlemark, Rego Park, N.Y.
(99-05 63rd Drive, New York, N.Y.)

Filed Mar. 7, 1961, Ser. No. 64,168

Term of patent 14 years

(Cl. D26—14)

FIG. 1

FIG. 2

FIG. 1 is a front perspective view of a television antenna showing my new design, and

FIGURE 2 is a top plan view thereof.

The dominant portions of my design reside in those portions shown in full lines.

I claim:

The ornamental design for a television antenna, substantially as shown and described.
